SETWORK GAUGE FOR SAWMILLS

Alvin Hahus, Origle, Ind., assignor of thirty-three and one-third per cent to James M. Etienne, Mount Pleasant, Ind.

Application December 2, 1946, Serial No. 713,589

2 Claims. (Cl. 143—124)

1

My invention relates to improvements in gages for sawmills of the type used for sawing logs longitudinally.

The invention is designed with the primary object in view of providing an accurate gage for mounting on the log carriage of such sawmills to indicate where to begin sawing off boards of different thicknesses from a log and where to stop so as to leave on the log carriage a core of predetermined thickness.

Another object is to provide a device of the character and for the purpose above set forth which is simple in construction, easy to install on such saw carriages, will not readily get out of order, and is comparatively inexpensive to manufacture.

Other and subordinate objects also comprehended by my invention, together with the precise nature of my improvements, will be readily understood when the succeeding description and claims are read with reference to the drawings accompanying and forming part of this specification.

In said drawings:

Figure 1 is a view in end elevation of a log carriage of a sawmill equipped with my improved gage in a preferred embodiment thereof, the gage being shown in front elevation.

Figure 2 is a view in front elevation of the casing partly broken away and shown in section and drawn to a larger scale.

Figure 3 is a view in front elevation of the dial disk with the setting arm thereon.

Figure 4 is a view in transverse section taken on the line 4—4 of Figure 1 and drawn to a larger scale.

Figure 5 is a view in rear elevation of the gage drawn to a larger scale and partly broken away and shown in section.

Figure 6 is a fragmentary view in longitudinal section of the lower end of the tubular guide and showing the roller bracket and the roller with the pull cable trained around the same.

Figure 7 is a view in perspective of the indicator hand.

Referring now to the drawings by numerals, my invention has been shown therein as forming an attachment for the usual log carriage 1 of a sawmill, illustrated conventionally as sufficient to a proper understanding of the invention, the log carriage 1 being adapted to travel on tracks, not shown, to feed a log 2 endwise to a disk saw 3. As is well known, such log carriages carry thereon relatively fixed head blocks, one of which is shown at 4, each with a sliding knee, as at 5,

2

thereon, the knees being adjustable in unison, by means not shown, toward the saw 4 into different set positions to feed the log 2 laterally different distances so as to set the log up to said saw to vary the thickness of boards to be cut from said log. Holding dogs, as at 6, for the log 2 are vertically adjustable on upright rack bars, as at 7, on the knees 5 and serve to hold the log 2 against the knees 5. Means, not shown, on the log carriage provide for turning the log 2 into 90° angular positions for cutting of boards from the four sides of the same. The head block 4 and knee 5 shown in the drawings are located at the far end of the log carriage 1, from the end shown in Figure 1, which is mentioned in passing for a reason presently clear.

The gage of my invention includes a circular, flat-sided casing 8 comprising a front circular face plate 9 formed with a reduced, concentric, rear annular flange 10, a cylindrical, axial hub 11 within said flange 10, and a rear, circular, rotatable closure plate 12 having a circumferentially grooved lateral flange 13 rotatably fitted over the flange 10, said closure plate 12 being formed with an axial hub 14 rotatably fitted over the hub 11, and said closure plate being further formed with an axial stud 15 extended forwardly through the hub 11 and rotatably fitted therein.

A radial bracket arm 16 depends from the rear side of the face plate 9 and by means of which, and bolts 17, the casing 8 is fastened in upright position to the rack bar 7 to face the log carriage 1 in a plane transverse thereto so that the face plate 9 is visible by an operator standing alongside said carriage.

A relatively smaller diameter, circular dial disk 18 is recessed into the front side of the face plate 9 concentrically thereof and for rotation therein and through which the stud 15 is rotatably extended.

A radial, straight-edge setting arm 19 suitably fixed to the front face of the dial disk 18 provides for setting said dial disk rotatably for a purpose presently apparent. A retractable 45 spring-pressed detent bolt 20 slidable in an outer end loop 21 on the setting arm 19 is provided for snap action engagement with peripheral detent notches 22 in the face plate 9 to hold said dial disk 18 set.

50 A circular series of graduations 23, representing inches, are provided on the front of the face plate 9, radially thereof, and around the dial disk 18, and with which the notches 22 register. The graduations 23 are numbered from zero at the top of the face plate 9 in ascending con-

secutive order counter-clockwise of said face plate. The setting arm 19 is adapted to be set with a leading edge 24 aligned with a selected graduation 23 for a purpose presently seen.

An indicator hand 25 is fastened by a screw 25' to the stud 15 to be rotated by said stud in front of the dial disk 18.

Returning now to the dial disk 18, said disk is provided with a plurality, five being shown, of circular, concentric series of radial graduations 26, 27, 28, 29, and 30, the outer and inner series 26, 30 being representative of one inch and two inches, respectively, and being so designated, as at 31, 32. The intermediate series 27, 28, 29 are representative of one and a different fraction of inches, respectively, and are correspondingly designated, as at 33, 34, 35. The graduations 26 to 30 are staggered relatively to avoid confusion in reading the same.

A pull cable 36 is wound around the flange 13 of the rear closure plate 12 with one end fast to said flange, said cable being extended downwardly from said flange through a tubular guide 37 depending from the flange 10 of the casing 1 alongside the knee 5. The tubular guide 37 is provided with a lower roller mounting bracket 38 with a roller 39 thereon around which the pull cable 36 is trained and extended rearwardly therefrom alongside the knee 5 with the other end thereof connected by an eye bolt 40 and wing nut 41 to a bracket 42 bolted, as at 43, to the rear end of the head block 5. As will be seen, from an inspection of Figure 4, the pull cable 36 is arranged to rotate the rear closure plate 12, when the knee 5 is adjusted forwardly and to thereby rotate the indicator hand 25, the direction of rotation being clockwise as viewed from the front of the gage.

A coil spring 44, in the casing 1, with the ends thereof suitably fastened to the hub 14 and to the front face plate 9, as at 45, 46, opposes such clockwise rotation of the closure plate 12 and indicator hand 25.

Suitable fasteners, as at 47, are provided for securing the tubular guide 37 to the knee 5.

Referring now to the use and operation of the described invention. Assuming that it is desired to cut a log, of any diameter within limits presently apparent, into one-inch boards and to leave a core, or tie 9 in. by 7 in. in cross section, the dial disk 18 is set clockwise, as viewed from the front of the gage, by means of the setting lever 19 until the straight edge 24 of said lever registers with the graduation 23 numbered 9 on the face plate 9, and with the knees 5 retracted and the log 2 positioned for lateral feed to set the same up to the saw 3, step by step. The log 2 is now set up to the saw 3 and a few slabs or boards sawed off the front side thereof to obtain a proper face on said side. During this setting up, as the knees 5 are adjusted forwardly, a pull is exerted on the pull cable 36 which rotates, in a manner previously described, the indicator hand 25 clockwise over the dial disk 18. When sufficient face has been obtained on the log 2, said log is turned on the head blocks 4 through an angle of 180° with the face obtained flat against the knees 5. The log 2 is again set up until the setup is sufficient to obtain a face on the now front side thereof and such setting up is stopped when the leading edge 47 of the indicator hand 25 registers with the first graduation 26 adjacent to the same and located forwardly of the setting arm 19. Boards are now sawed off with a thickness of one inch

gaged by setting up the log 2 to the saw until the leading edge 47 of the indicator hand 25 registers with successive graduations 26 of the inch representing series and such sawing off of boards is continued until the leading edge 47 of the indicator hand 25 is aligned with the edge 24 of the setting arm 19. At this point, the sawing is stopped and a core, or tie 9 in. thick one way is left on the knees 5. The log is next turned through an angle of 90° on the head blocks 4 to present an unsawed side to the saw 3. The setting arm 19 is then set clockwise to register the edge 24 thereof with the graduation in the series 26 numbered 7 on the face plate, and the operations described in the foregoing relative to setting up the log 2 and sawing off boards from the same is repeated. The log 2 is then again turned through an angle of 180° on the head blocks 4 to present the remaining unsawed side thereof to the saw 3 and the setting up and sawing operations again repeated as described, and at the termination of which the core, or tie on the head blocks 4 is left with a thickness of 7 in. between two opposite sides thereof and a thickness of 9 in. between the other two sides of the same.

Obviously, by registering the setting arm 19 with selected graduations of the series 23 and utilizing the graduations 27, 28, 29, 30, otherwise following the operations described, the width of boards of other thicknesses may be accurately gaged and cores of different widths obtained.

As will, of course, be understood, to attain cores or ties of different thicknesses by operation of the invention as described, the series of graduations 23 are arranged so that when the setting arm 19 is registered with a selected one of the series, and the indicator hand 25 is aligned with said hand, as described, the knee 5 will be positioned from the saw 3 a distance corresponding in inches to the number of inches represented by the selected graduation in the series, plus, of course, the thickness of the saw 3 for each inch of distance.

A portion of each series of graduations 26 to 30, immediately in front of the setting arm 19, is colored as represented at 49, 50, 51, 52, 53, to the first graduation in front of said arm. This is in the nature of a safety provision for preventing an operator from starting a sawing operation while the indicator hand 25 is between the setting arm 19 and the first graduation on the dial disk 18 in front of said arm.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. The combination with the knee of a sawmill carriage movable across the carriage step by step for setting a log relative to the sawmill, of means for predetermining the number and degree of steps of movement of said knee to cut boards of different width from the log and a core of a predetermined thickness comprising a circular plate mounted on said knee with an edge series of graduations thereon numbered in correspondence with different thicknesses of cores to be cut, a dial on said plate having circular concentric series of graduations thereon for gaging different thicknesses of boards to be

cut, and being rotatably settable into different positions in accordance with different thicknesses of cores to be cut, a dial setting arm fast thereon and movable into registration with the edge graduations selectively in accordance with the thickness of a core to be cut, an indicator sweep hand, a grooved circular member rotatably mounted on said plate and carrying said hand, and a pull cable wound on said member and connected to said carriage to impart intermittent rotation to said member upon step-by-step movement of said knee for swinging said hand over said dial step-by-step into registration with said graduations successively whereby to gauge the thickness of boards to be cut and align said hand with said arm when a core of predetermined thickness has been cut.

2. The combination with the knee of a sawmill carriage movable across the carriage step by step for setting a log relative to the sawmill, of means for predetermining the number and degree of steps of movement of said knee to cut boards of different width from the log and a core of a predetermined thickness comprising a circular plate mounted on said knee with an edge series of graduations thereon numbered in correspondence with different thicknesses of cores to be cut, a dial on said plate having circular concentric series of graduations thereon for gaging different thicknesses of boards to be cut, and being rotatably settable into different positions in accordance with different thicknesses of cores to be cut, a dial setting arm

5
